Primary Examiner — T Chase Nelson*Assistant Examiner* — Jonathan J. Han(74) *Attorney, Agent, or Firm* — DeLio Peterson & Curcio LLC; Robert Curcio(57) **CLAIM**

We claim the ornamental design for a “firearm magazine”, as shown and described.

DESCRIPTION

FIG. 1 is a first side view of the firearm magazine according to the present invention;

FIG. 2 is a second side view of the firearm magazine according to the present invention;

FIG. 3 is a back view of the firearm magazine according to the present invention;

FIG. 4 is a front or muzzle view of the firearm magazine according to the present invention;

FIG. 5 is a front perspective view of the firearm magazine according to the present invention;

FIG. 6 is a top view of the firearm magazine according to the present invention; and,

FIG. 7 is a bottom view of the firearm magazine according to the present invention.
